UNITED STATES PATENT OFFICE.

SEVERN D. SPRONG AND WALTER E. MCCOY, OF NEW YORK, N. Y., ASSIGNEES OF ONE-
THIRD TO FRANK W. SMITH, OF NEW YORK, N. Y.

ELECTRIC FUSE.

1,094,030.

Specification of Letters Patent. Patented Apr. 21, 1914.

Application filed September 6, 1912. Serial No. 718,826.

To all whom it may concern:

Be it known that we, SEVERN D. SPRONG and WALTER E. McCoy, citizens of the United States, residing at New York, in the county of New York and State of New York, have invented a certain new and useful Improvement in Electric Fuses, of which the following is a specification.

The invention relates to electric fuses, and provides a construction whereby with two circuits, including two fuses and the minimum number of circuit terminals, the blowing of the fuse in one circuit will determine the rupture of the fuse in the other circuit: the said construction comprising a U-shaped fuse strip, disposed in a suitable closed tube or casing, into which three circuit terminals, each of greater conductivity than said strip, are led and directly connected respectively to the loop and ends of said strip.

In the accompanying drawings—Figure 1 is a longitudinal section of our electric fuse, and Fig. 2 is a similar view of a modification thereof.

Similar letters of reference indicate like parts.

The fuse case A may be cylindrical and of any suitable material. The fuse strip B is in loop or U-form with its arms a, b connected at their ends to circuit terminals C, D. Another circuit terminal E at the opposite end of the fuse case is connected to the strip B at a point e, preferably midway between the arms. The conductivity of the fuse strip is to be less than that of either of the circuit terminals C, D, E. In the form shown in Fig. 1, the terminals C, D are straight and extend through a plug F of plaster or other refractory insulating material, which closes the end of the case A. The terminal E, also straight, extends through a similar plug G at the opposite end of the case. When it is desired to bring the parallel arms a, b of the fuse strip nearer together, the terminals C, D may be inclined toward one another and carried through in-

clined passages in a supporting disk H of porcelain or similar material placed inside the case, as shown in Fig. 2.

We here show our fuse disposed in two mutually dependent circuits I, II, each including a generator, J and K. Circuit I includes generator J, terminals C, E and fuse arm a. Circuit II includes generator K, terminals D, E and fuse arm b. When either fuse arm blows, it causes a rupture of the other arm by reason of its proximity thereto; so that while the two circuits are normally independent, any cause producing a blowing of the fuse in one of them, will determine a break in the continuity of the other.

We claim:

1. An electric fuse, comprising a tube, a closure of insulating material at each end of said tube, one of said closures having two inwardly converging passages, two circuit terminals disposed in said passages, a single circuit terminal entering said tube through the other closure, and a U-shaped fuse strip having its loop connected to said single terminal and its ends connected respectively to said two terminals.

2. An electric fuse, comprising a tube, plugs of insulating material in the ends of said tube, a disk of refractory material in said tube and having inwardly converging passages, two circuit terminals extending through one of said plugs and said passages, a single circuit terminal entering said tube through the other plug, and a U-shaped fuse strip having its loop connected to said single terminal and its ends connected to said two terminals.

In testimony whereof we have affixed our signatures in presence of two witnesses.

SEVERN D. SPRONG.
WALTER E. MCCOY.
